UNITED STATES PATENT OFFICE.

YUYEMON IKEDA, OF GARDENA, CALIFORNIA.

IGNITING DEVICE.

Application filed February 19, 1923. Serial No. 620,065.

To all whom it may concern:

Be it known that I, YUYEMON IKEDA, a subject of the Emperor of Japan, residing at Gardena, in the county of Los Angeles and State of California, have invented a new and useful Igniting Device, of which the following is a specification.

This invention relates to means intended and designed to cause the ignition of combustible elements for the purpose of producing fire or for communicating the same, and has for its object to provide a substitute for matches; the device comprising a receptacle for combustible pellets, mechanism for ejecting the pellets consecutively for each combustible charge, and mechanism for igniting the pellets as they are ejected from the body of the receptacle.

Each pellet comprises a combustible charge and is adapted to burn for the same period of time as an ordinary match.

The invention further comprises mechanism for igniting the combustible pellets on a prepared paper similar to the ordinary safety match, and mechanism for renewing the paper with a fresh portion as it becomes worn.

The mechanism further comprises means for breaking up and discharging the ashes of combustion at the termination thereof so that the delivery mechanism may be capable of receiving a new pellet when withdrawn to inoperative position within the receptacle.

The invention also comprises other novel features as more fully described in the appended specification and defined in the claims.

In the accompanying drawings: Figure 1 is a vertical and side view of the preferred form of my improved ignition device. Fig. 2 is an end elevation of the same. Fig. 3 is a vertical and sectional view enlarged and showing the delivery mechanism in inoperative position. Fig. 4 is a perspective detail view of the spring and follower which serves to force the pellets to the delivery mechanism. Fig. 5 is a top plan view of the device. Fig. 6 is a fragmentary and sectional detail view of the device and showing the delivery mechanism in operative position. Fig. 7 is a perspective detail view of the releasing latch. Fig. 8 is an end view of the igniting cover. Fig. 9 is a detail and front view of the same. Fig. 10 is an enlarged and detail end view of the plunger. Fig. 11 is a sectional detail view

of the same. Fig. 12 is a vertical and sectional view of a modified form of the invention showing a frictional igniting element wound upon a reel. Fig. 13 is a fragmentary detail view showing the method of mounting the reel.

Referring to the drawings, the device consists of a receptacle 21, having an emission port 22, for pellets 23. A cover 24, for the emission port, is hinged to the receptacle, and has a corrugated surface 25, for frictional engagement with a pellet for the purpose of igniting the same. A plunger 26, having an enlarged cylindrical end 27, is 70 slidably mounted within the receptacle in compartment 28, formed by the partition 29. A spring 30, interposed between the receptacle wall and the cylindrical end of the plunger, tends to force the plunger outwardly through emission port 22. The delivery end of the plunger is formed with a recess or pocket 31, adapted to receive a single pellet. The pocket is eccentric relative to the axis of the plunger so that the 80 pellet contained therein will project from the pocket sufficiently to engage with the igniting surface 25, of cover 24. A spring 32 serves to maintain the cover in operative engagement with the pellet. The plunger is 85 provided with an arm 33, projecting through slot 34 in the wall of the receptacle, and projecting through slot 35 in latch member 36. The arm 33 affords a means for manually manipulating the plunger to its inoperative position within the receptacle.

The latch member 36 is mounted on the pivot bar 37, and its outer extremity 38 extends over the emission port 22 in operative position of the latch member. A detent 95 lever 39, also mounted on pivot bar 37, serves to engage with the cylindrical portion 27, of plunger 26, to retain the same within the receptacle and against the tension of spring 30.

Latch member 36 and detent lever 39 are maintained in operative position by a spring 40. The latch member extremity 38, when the plunger is extended from the emission port, projects in slot 41 in the plunger, and, 105 as the plunger is withdrawn within the receptacle, serves to break up and remove the ash remaining in the plunger pocket after combustion. Slot 41 and slots 42, serve first to supply sufficient air to maintain combustion, and secondly, to provide an outlet for the ashes of combustion.

The receptacle 21, adjacent to emission port 22, is provided with a wall extension 20, serving, in the normal position of the plunger, to partly cover the pocket 31, so that but one pellet will be contained therein, and the same will not become ignited by contact with the edge of the emission port when the plunger is released. On withdrawing the plunger within the receptacle, the plunger is drawn back sufficiently to allow a pellet to enter the pocket in the end of the plunger; the plunger then advancing until the detent lever 39 engages with part 27 of the plunger.

For protection of the flame during combustion of the pellet, I provide a windshield 43, mounted on the side of the receptacle and slidable to extend above the edge of the box, or body, of the receptacle. Shield 43 is secured by members 44, protecting from the body, and has an ear 45, projecting over the edge of the receptacle and by which the shield may be manually extended to operative position. Within the receptacle, the follower 46, actuated by spring 47, serves to force the pellets into the delivery pocket. A plate member 48, on the opposite end of spring 47, is reversible in position relative to follower 46, so that either may serve the same purpose, and are further removable from the receptacle when cover 49 is in open position, so that the receptacle may be quickly refilled with a new supply of pellets. The receptacle is provided with projecting flanges 50, serving to protect the pocket of the user from wear.

In use, the receptacle being filled with pellets, the operator depresses lever ends 51, of latch member 36 and detent member 39, thereby releasing the plunger, which is then forced outward by spring 30. The plunger forces open the cover 24, and, as the pellet emerges from the emission port, it engages with frictional surface 25, of the cover, and is ignited. Upon ignition, the pellet, being supported by the cover and within the plunger pocket, will burn until consumed. After combustion, the operator grasps the arm 33 and forces the plunger within the receptacle. The ash remaining within the pocket, is broken up by member 38; the particles of the ash passing out through the slots in the plunger. The plunger is forced inward until the pocket registers with the interior of the receptacle, allowing a pellet to enter, and is then retained by the detent member 39.

In the modified form shown in Fig. 12, the receptacle 52, having an emission orifice 53, and a spring-actuated cover 54, is partitioned to form the pellet chamber 55, and a chamber 56, containing a roll of paper 57, having the surface thereof prepared with a friction coating such as that which is used for igniting safety matches. The web of

paper 57, passes through an orifice 58, and between clamps 59 and the inner face of the cover. The paper with the prepared igniting surface is thus held tightly against the cover for approximately two-thirds of its length. The roll of paper is supported by trunnions, one of which is fixed to the receptacle casing, the other being mounted on a spring 60, and projecting into the chamber 56. The other operative parts are similar to their equivalent parts shown in Figs. 1 to 11, inclusive. This form is intended to use with safety pellets which will ignite only by contact with the frictional surface on the paper. The combustion of the pellet occurs at the extremity of the plunger and the extremity of the cover. When the igniting surface of the paper is worn, it is drawn through the aperture and beneath the clamps to expose a new section of the surface. The opening 61, through which a new roll may be inserted, is provided with a sliding cover 62.

From the foregoing description and drawings, it may be seen that I have provided simple and efficient means for igniting a combustible pellet, for maintaining combustion of the same until consumed, and for removing the ashes after the combustion terminates; the invention including a receptacle and operative elements, and all within the dimensions of an ordinary match-box.

What is claimed is:

1. The combination with a pellet receptacle having an emission orifice, of a cover hinged to the top of the receptacle and adjacent to the orifice, a spring normally holding the cover over the orifice, a frictional corrugated surface on the inner side of the cover, a plunger sliding in the receptacle, and having a pellet pocket in the extremity thereof, an enlarged cylindrical end on the plunger and within the receptacle, a spring interposed between the cylindrical end and the wall of the receptacle, a latch to retain the plunger within the receptacle in inoperative position, and a spring to actuate the latch.

2. The combination with a pellet receptacle having an emission orifice, of a cover hinged to the top of the receptacle and adjacent to the emission orifice, a spring normally holding the cover over the orifice, a frictional igniting surface on the inner side of the cover, a plunger slidably mounted within the receptacle and having a pellet pocket in the extremity thereof, an enlarged cylindrical end section on the plunger, a spring interposed between the cylindrical end and the receptacle wall, a partition wall enclosing the spring and plunger in its inoperative position within the receptacle, a latch member to retain the plunger within the receptacle in inoperative position, and a de-

tent lug on the latch member engaging with the cylindrical portion of the plunger, a spring to actuate the latch, and a lug projecting from the plunger for manually re-

tracting the same within the receptacle.

3. The combination with a receptacle having an emission orifice, of a cover hingedly connected to the top of the receptacle and adjacent to the emission orifice, a spring normally holding the cover over the orifice, a frictional igniting surface on the inner side of the cover, a partition wall forming a separate compartment in the receptacle, a plunger slidably mounted in the plunger compartment, said plunger compartment having a slot in the wall thereof, an enlarged cylindrical section forming one end of the plunger, a pellet pocket in the opposite end of the plunger, a spring interposed between the cylindrical section of the plunger and the wall of the receptacle, a latch member to retain the plunger within the receptacle in inoperative position, said pellet pocket registering with the interior of the receptacle in inoperative position, and a spring to actuate the latch member.

4. The combination with a pellet receptacle having an emission orifice, of a cover hingedly connected to the top of the receptacle and normally covering the emission orifice, a spring to actuate the cover, a frictional igniting surface on the inner side of the cover, a plunger slidably mounted in the receptacle and adapted to extend through the emission orifice, a spring to actuate the plunger, a pellet pocket in the end of the plunger and eccentric with the axis thereof and arranged so that a pellet will project from the pocket and into contact with the cover, means for manually retracting the plunger within the receptacle, said pellet pocket registering with the interior of the receptacle in the retracted position, and a spring-actuated catch to hold the plunger within the receptacle in inoperative position.

5. The combination with a pellet receptacle having an emission orifice, of a spring-actuated igniter disposed adjacent to the orifice, a plunger slidably mounted within the receptacle and adapted to project through the orifice, a pellet pocket in the end of the plunger and open at the side in opposed relation to the igniter, a spring to actuate the plunger, and means for holding the plunger within the receptacle and against the tension of its actuating spring.

6. The combination with a pellet receptacle having an emission orifice, of a spring-actuated igniter disposed adjacent to the orifice and normally covering the same, a plunger within the receptacle and having a pellet pocket in the end thereof, said pocket opening in opposed relation to the igniter in the extended position of the plun-

ger, a spring to actuate the plunger, means for manually withdrawing the plunger within the receptacle, and detent means for the plunger in the retracted position.

7. The combination with a pellet receptacle having an emission orifice, of a spring-actuated igniter adjacent to the orifice and normally covering the same, a plunger within the receptacle and having a pellet pocket in opposed relation to the igniter in the extended position of the plunger, a spring to actuate the plunger, said plunger having a slot in the end thereof and extending deeper than the pellet pocket, a spring-actuated latch-member to retain the plunger within the receptacle in inoperative position, and a projecting lug on the latch member adapted to extend in the longitudinal slot in the end of the plunger and beneath the pellet pocket.

8. The combination with a receptacle having an emission orifice, a spring-actuated igniter adjacent to the orifice, a plunger working in the receptacle and having a pellet pocket in opposed relation to the igniter in the extended position of the plunger, a spring to actuate the plunger, means for retaining the plunger within the receptacle in inoperative position, a reel compartment in the receptacle, adapted to contain a roll of igniting paper, said receptacle having an orifice for the web of the igniting paper, and clamps on the igniter to hold the igniting paper thereon.

9. The combination with a receptacle having an emission orifice, of a spring-actuated igniter adjacent to the orifice and normally covering the same, a plunger slidably mounted within the receptacle and having a pellet pocket in one end thereof in opposed relation to the igniter in the extended position of the plunger, a spring to actuate the plunger and tending to force the plunger outwardly through the emission orifice, a spring-actuated latch member to retain the plunger within the receptacle in its inoperative position, said plunger having a longitudinal slot extending below the pellet pocket, a projecting lug on the latch member and adapted to extend within the slot in the extended position of the plunger, said pellet pocket being in registration with the interior of the receptacle in the retracted position of the plunger, and adapted to receive one pellet at a time, a follower within the receptacle to force the pellets into the pellet pocket, a spring to actuate the follower, and a sliding cover to retain the spring and follower within the receptacle.

10. The combination with a pellet receptacle having an emission orifice, of a spring-actuated igniter adjacent to the orifice and normally covering the same, a plunger slidably mounted within the receptacle and having a pellet pocket in one end thereof

in opposed relation to the igniter in the extended position of the plunger, a spring to force the plunger through the emission orifice, means for retaining the plunger within the receptacle and against the tension of the spring, said pellet pocket being in registration with the interior of the receptacle in the retracted position of the plunger, a spring-actuated follower independently

mounted within the receptacle and serving to force the pellets into the pellet pocket, said follower being removable from the receptacle, and a sliding cover to retain the spring-actuated follower within the receptacle. ¹⁰

Signed this 27th day of January, 1923.

YUYEMON IKEDA.
